DOOR LOCK

Walter R. Schlage, Burlingame, Calif., assignor
to Schlage Lock Company, San Francisco,
Calif., a corporation of California

Application May 26, 1941, Serial No. 395,192

4 Claims. (Cl. 292—169)

This invention relates to door locks, and especially to improvements on the structure disclosed in my former Patent No. 2,062,766, entitled "Door lock," issued December 1, 1936.

In the patent above referred to a door lock is disclosed which embodies a housing and a retractor plate slidably mounted in the housing to extend or retract a latch bolt. A spindle is journaled in and extends through the housing and an opening formed in the retractor plate, and on the spindle is a roll back member which engages the retractor plate; and rearwardly of the rollback is a slot into which a portion of the retractor plate extends. This portion of the retractor plate forms an interlock with the spindle and secures the spindle against endwise removal from the housing during all normal operations of the lock. A stop member carried by the retractor plate prevents disengagement of the interlock, but the stop member may be manually released, and the retractor plate may thus be moved to a position beyond a normal retracted position to release the interlock and thereby permit removal of the spindle.

The object of the present invention is generally to improve and simplify the construction and operation of door locks of the character described, and particularly to provide an improved form of stop member carried by the housing, whereby the interlock between the retractor plate and the spindle may be automatically retained during all normal operations of the lock and manually released when removal of the spindle is required.

The invention is shown by way of illustration in the accompanying drawings, in which

Fig. 1 is a horizontal longitudinal section of the door lock showing it mounted in a door;

Fig. 2 is a vertical longitudinal section showing the lock mounted in a door;

Fig. 3 is a section similar to Fig. 1, showing the latch bolt B manually forced inwardly beyond a normal retracted position to permit removal of the spindle;

Fig. 4 is a perspective view of the door lock housing, said view being partially broken away and partially in section;

Fig. 5 is a perspective view of the U-shaped frame forming a part of the lock housing;

Fig. 6 is a perspective view of the latch bolt B and the retractor plate b to which it is attached;

Fig. 7 is a perspective view of the head member secured to the rear end of the retractor plate;

Fig. 8 is a perspective view of a dogging member carried by the head shown in Fig. 7;

Fig. 9 is a perspective view of a stop member;

Fig. 10 is a perspective view of a spindle;

Fig. 11 is a perspective view of an actuator; and

Fig. 12 is a perspective view of a key actuated tumbler cylinder.

Referring to the drawings in detail, and particularly to Figs. 1, 3, 4 and 5, A indicates a portion of a door to which is suitably secured a lock housing consisting of two side plates 2 and 3, which are joined at their outer ends by a face plate 4. Secured between the plates 2 and 3 of the lock housing is a U-shaped frame (see Fig. 5) consisting of upper and lower horizontally extending arms 5 and 6 which are connected at the rear ends by an end bar 7. The forward ends are provided with right-angularly bent lugs 8—8 and they are secured to the face plate 5 by rivets, counter-sunk screws or the like, such as indicated at 9.

A latch bolt, indicated at B, is employed. This is best shown in Figs. 1, 2, 3 and 6. It is attached to a retractor plate generally indicated at b. This plate is rectangular in shape and has two projecting edges 10—10 which extend into guide slots 11—11 formed in the arms 5 and 6 of the U-shaped frame. An elongated opening 12 is formed in the plate, and rearwardly thereof a head member 14 which is notched as at 15 to straddle a bar which will hereinafter be referred to as the actuator. The head 14, which is U-shaped in cross section (see Fig. 7), is riveted or otherwise secured to the retractor plate b, and it forms a pair of shoulders 16—16 which are adapted to be engaged by a rollback member hereinafter to be described.

Formed on the side plates 2 and 3 of the lock housing are outwardly extending bearing hubs 20 and 21, in which is journaled a spindle generally indicated at D. This spindle is best shown in Figs. 1, 2, 3 and 10. A central portion indicated at 23 is enlarged in diameter, while the inner and outer ends of the spindle are reduced in diameter, as indicated at 24. The central enlarged portion is cross-slotted as at 25, and a rollback member 26 is thus formed. The opposite sides of the cross slot are notched as shown at 27, and these notches are provided for the reception of a dogging member C (see Fig. 8).

A pair of knobs 30 and 31 are secured in any suitable manner on the opposite ends of the spindle. The knob 30 will hereinafter be referred to as the outer knob, and the knob 31 as the inner knob. Insertible through the inner end of

the spindle is a bar 32 which is circular in cross section and snugly fits the interior of the spindle, which is tubular. A collar 33 is formed on the outer end of said bar and engages the end of the spindle. This collar is overlaid by an annular shoulder 34 of the knob and the bar is thus secured against endwise movement within the spindle, but it is free to rotate, and means in the form of a turnpiece 35 is formed on the outer end of the bar and projects beyond the face of the knob 31 to permit it to be grasped to rotate the bar. The bar is best shown in Figs. 1, 2, 3 and 11. Adjacent its inner end it is cross-slotted on opposite sides to form a flat bar 36 which will hereinafter be referred to as the actuator. Beyond that is a cylindrical extension 37, and on the end thereof is formed a lug 38.

Extending through the outer knob 30 and into the tubular spindle is a key actuated tumbler cylinder 39 (see Figs. 1, 2, 3 and 12). The spindle proper functions as a housing for the cylinder and the tumblers 40 normally project into a slot 41 formed in the spindle, and thus secures the cylinder against rotation within the spindle. However, by inserting a key, the tumblers 40 are retracted and the cylinder is then free to rotate, and when it is rotated a pair of lugs 42 formed on the inner end engage the lug 38 of the actuator, and rotation is thereby imparted to the actuator by the key actuated cylinder. The key actuated tumbler cylinder has a collar 45 formed on its outer end, and this is overlaid by an annular shoulder 46 formed on the knob 30. The key cylinder is thus secured against endwise movement but is free to rotate within the spindle when a key is inserted.

By referring to Fig. 6, it will be noted that the rear end of the retractor plate *b* is longitudinally slotted, as shown at 12a. Hence when the head 14 is applied and riveted or otherwise secured to the retractor plate, a passage 12a will be formed within the head 14 and an opening 12b is accordingly formed in the outer end of the head to communicate with said opening. In Fig. 8 it will be noted that the dogging member *C* consists of a plate 48 which is adapted to enter the opening 12b in the head and to extend into the passage 12a of the retractor plate and to be guided thereby. On the outer end of the plate 48 is a head member 49. On each side of the head is formed a dogging lug *C* and on the outer end of the head is formed a lug 50 which functions to retain the spring 51, hereinafter to be referred to.

The dogs *C*, as previously stated, are provided for the purpose of entering the slots 27 of the spindle and when they do so, they dog the spindle against rotation, and as the knobs 30 and 31 are rigidly secured to the spindle, they will also be dogged and the door cannot be opened by rotation of either knob. The dogging position of the spindle is shown in Fig. 1. In this instance the latch bolt *B* is fully projected and the door is accordingly locked as it cannot be opened either from the inside or the outside, as the knobs and the spindle are dogged against rotation.

The door, however, may be opened from either the inside or the outside, as will now be described; from the inside the door can be opened by gripping the turnpiece 35 and rotating it a quarter of a revolution. In so doing the actuator bar 36 on the bar 32 will engage the inner end of the plate 48 which carries the dogs *C*, and thus force it rearwardly with relation to the retractor plate. In so doing, the dogs will be retracted

from the slots 27 formed in the spindle and the spindle may then be rotated by either knob to retract the latch bolt *B*. Such rotation of the spindle causes the rollback member 26 formed on the spindle to engage one or another of the shoulders 16 of the head 14, and the entire retractor plate, together with the dogging member, is thus moved rearwardly and the latch bolt is retracted; and when the knob by which the spindle is rotated is released the retractor plate and latch bolt will return to normal or projected position by means of the spring 51 and a second pair of springs indicated at 52. That is, the head member 14 is provided with two lugs 53 and these serve to retain the springs 52.

If the lock assumes the dogged or locked position shown in Fig. 1, and a person desires to enter from the outside, it can be accomplished by the insertion of the proper key. Such insertion will cause retraction of the tumblers 40 and the tumbler cylinder may then be rotated. Such rotation causes the lugs 42 at the inner end of the tumbler cylinder to engage the lug 38 and the actuator bar 36 is thus rotated to force the plate 48 which carries the dogs rearwardly, thereby pulling the dogs out of the slots 27 of the spindle and releasing it for rotation.

By referring to Fig. 10 it will be noted that the cross slot 25 which forms the rollback member 26 is fairly wide. In fact, it is just sufficiently wide to permit the U-shaped head member 14 to enter said slot so that the shoulders 16 thereof may engage the face of the rollback member 26. The actual diameter of the spindle together with the rollback member is clearly shown in Fig. 2; that is, the dotted lines forming a continuation of the rollback member indicate the diameter of the spindle and this view also shows the distance to which the head member on the retractor plate enters the slot 25.

This entering portion of the head is important. First of all, it permits the shoulders 16 to engage the rollback member 26; secondly, it forms an interlock with the spindle, preventing its endwise removal from the door lock housing; and the spindle cannot be removed until the retractor plate *b* carrying the head member 14 is moved to a point where the shoulder 16 assumes a position rearwardly of the cross-slotted central portion of the spindle. Such rearward movement cannot take place under the ordinary operations to which the lock is subject, as such rearward movement is limited by a stop member generally indicated at *E* (see Figs. 1, 2, 3 and 9). The stop member consists of a base plate 55 which normally rests on the inner end bar 7 of the U-shaped frame of the lock housing. The plate 55 has two forwardly extending arms 56 and these arms normally assume the position shown in Fig. 1. In this position the arms will engage the inner end of the head member 14 and thus limit inward movement of the retractor plate and the latch bolt, and this inward movement is not sufficient to release the interlock formed between the head 14 and the cross slot 25 of the spindle. The stop member *E* performs two functions, the main function being that of limiting inward movement of the retractor plate and the latch bolt, and the second function being that of forming a spring seat for the three springs indicated at 51 and 52. These springs normally maintain the retractor plate and latch bolt in the projected position shown in Fig. 1, and they furthermore retain the stop member *E* in the position also shown in Fig. 1.

If it is desired to remove the spindle, for instance, for the purpose of repairing or inspecting the lock, it can be accomplished from the inner face of the door lock by inserting a pin 60 through a hole 61 formed in the inside plate 3 of the lock housing; when the pin is thus inserted and pushed inwardly it engages one of the legs or arms 56 of the stop member, as clearly shown in Fig. 3, and it imparts a rocking movement thereto which swings the arms 56 out of alignment with the inner end of the head member 14 of the retractor plate. In this position an operator can exert finger pressure on the latch bolt B and push it inwardly beyond a normal retracted position, as shown in Fig. 3. In this position the shoulders 16 of the head member 14 will assume a position rearwardly of the enlarged portion of the spindle 23 and the spindle may then be removed endwise through the opening 12 formed in the retractor plate 6 and the bearings 20 and 21 of the lock housing—that is, provided one or another of the knobs has previously been removed.

The movement imparted to the stop member by means of the pin 60 is a rocking movement, and by imparting the rocking movement as previously stated, the arms 56 are moved out of the path of travel of the inner end of the head member 14. The movement, however, that the pin is removed, the stop member will return to the normal position shown in Fig. 1, as the pressure of the springs 51 and 52 will return it to this position. The rocking movement is identical to a pivotal movement, but no pivot is required as the base of the stop member or plate 55 may obviously be rocked on the bar 7, thereby eliminating any hinged or pivotal connection.

In my prior Patent No. 2,062,766, a stop member was also employed normally to limit inward movement of the retractor plate and the latch bolt carried thereby. The stop member was, however, pivotally mounted on the retractor plate and was movable with the retractor plate. While the structure functioned to perfection, its structure and mounting were complicated when comparison is made to the present stop member. This stop member is supported by the housing and requires no extra springs to maintain it in normal position. Thus it is more substantial and far simpler to construct and to mount in the lock. This stop member is the main improved feature of the present application.

While certain features of my invention have been more or less specifically described and illustrated, I wish it understood that changes may be resorted to within the scope of the appended claims, and that the materials and finish of the several parts may be such as the experience of the manufacturer or varying conditions of use may demand.

Having thus described my invention, what I claim and desire to secure by Letters Patent is:

1. In a lock of the character described, a hous-

ing, a latch bolt mechanism mounted for reciprocal movement therein, a rockable stop member normally disposed in the path of movement of the latch bolt mechanism to limit inward movement of said mechanism with relation to the housing, said stop member adapted to be manually rocked to assume a position out of the path of movement of the latch bolt mechanism, to permit extended inward movement thereof beyond a normal retracted position, and a common spring interposed between the latch bolt mechanism and the rockable stop member, said spring normally tending to maintain the latch bolt mechanism in a projected position and the stop member in a position to limit inward movement of the latch bolt mechanism.

2. In a lock of the character described, a housing, a latch bolt mechanism mounted for reciprocal movement therein, a stop member carried by the housing and normally disposed in the path of movement of the latch bolt mechanism to limit inward movement of said mechanism with relation to the housing, said stop member being movable to permit extended inward movement of the latch bolt mechanism beyond a normal retracted position, and a common spring interposed between the latch bolt mechanism and the stop member, said spring normally tending to maintain the latch bolt mechanism in a projected position and the stop member in a position to limit inward movement of the latch bolt mechanism.

3. In a lock of the character described, a housing, a latch bolt mechanism mounted for reciprocal movement therein, said housing having an inner end, a plate supported at the inner end of the housing, an arm on said plate extending into the path of movement of the latch bolt mechanism to limit inward movement thereof beyond a normal retracted position, said plate and arm being rockable to move the arm out of the path of movement of the latch bolt mechanism to permit extended inward movement of the latch bolt mechanism, and a spring interposed between the latch bolt mechanism and the plate, said spring normally maintaining the latch bolt in an extended position and the arm in a position to limit inward movement of the latch bolt mechanism.

4. In a lock of the character described, a housing, a latch bolt mechanism mounted for reciprocal movement therein, said housing having an inner end, a plate supported at the inner end of the housing, an arm on said plate extending into the path of movement of the latch bolt mechanism to limit inward movement thereof beyond a normal retracted position, said plate and arm being rockable to move the arm out of the path of movement of the latch bolt mechanism to permit extended inward movement of the latch bolt mechanism, and a spring engageable with the rockable plate to normally maintain the arm in a position to limit inward movement of the latch bolt mechanism.

WALTER R. SCHLAGE.
